UNITED STATES PATENT OFFICE

GEORGE RUDSTON BROWN, OF CROYDON, NEAR SYDNEY, NEW SOUTH WALES,
AUSTRALIA

APPARATUS FOR ELECTRIC-CURRENT DISTRIBUTION

Application filed August 31, 1926, Serial No. 182,713, and in Australia October 2, 1925.

This invention relates to apparatus usable in connection with electric current distribution. The object of the invention is to provide means which whilst being adaptable for electric current distribution in certain specific cases is also usable with certain elements as a switch box, junction box, fuse box, coupling box, or test, inspection or other box or otherwise, the box itself and appurtenant parts being interchangeable so that the apparatus will be serviceable for providing electric current to circuits as required.

The apparatus comprises a base, a cover plate, and an integral element adapted to have associated therewith variable elements whereby electric current distribution may be effected.

Referring to the accompanying drawings in which the invention is illustrated, Fig. 1 is a perspective view of the integral element associated with a base plate; Fig. 2 a perspective view partly in section showing the integral element with cover and base and certain electric current distribution components associated with the element; Figs. 3 and 4 respectively cross-sections on planes 3-3 and 4-4, Fig. 2; Fig. 5 perspective view of the integral element with base plate, the element being adapted for use in connection with switch means; Fig. 6 perspective view partly in section showing the element of Fig. 5 and electric current distribution components associated therewith together with a cover and base; Figs. 7 and 8 respectively cross sections on planes 7-7 and 8-8, Fig. 6; Figs. 9, 10 and 11 detail views illustrative of side electric connection means for the base inclusive of ornamentation means shown in Fig. 9.

With reference to Figs. 1 to 4 the cover 1 is of metal; its head has a tapped opening 2 and its foot is formed with a flange 3 to seat against the flange 4 on the head of the metal base 5. Preferably the interior face of the cover is furnished with suitable electrical insulating material 6. An integral element 7 is adapted to be carried centrally within the cover 1 and base 5. Such element 7 is preferably constructed of metal and is U-shaped having lateral foot flanges 8 and 9. At its head it is preferably formed with a boss 10

from which projects the vertical tubular member 11 having an external screw-thread 12. Such member 11 projects through the tapped opening 2 of the cover 1 which opening is of larger diameter than the member 11. The outer face of the member 7 is furnished with electrical insulating material 13, and the bottom of the base 5 is suitably formed to receive the holed plate 14 to which the element 7 may be attached by means of the angled brackets 15 and rivets 16 as well as screws 17 or otherwise. If required the base 5 may be connected to a base plate 18 by the screws 19 or other suitable means; the said base plate 18 will be hereinafter described. Components 69 of suitable type for electric current distribution work may be attached by the screws 73 or otherwise to the element 7.

In Figs. 5 to 8, the integral element 7 is shown with openings 89 in its opposite side walls, such openings being intended to serve as bearings for parts of any rotatable switch gear which may be utilized with the apparatus. When such switch gear is used it is also preferred to provide in association with the element 7 the shield 20 one end of which is suitably attached to the head of the element 7 and the other end thereof to the holed plate 14. Such plate 14 is shown in Figs. 7 and 8 with an opening 21. The shield 20 may serve the purpose of protecting the electric lead wires from contact with the switch mechanism. If required one end of the element 7 may be extended as at 22 to receive parts, say 23, of switch mechanism to be used. One type of switch operative means 96 is shown in Fig. 7, part of such means being fitted in the openings 89 in the element 7 and turnable therein.

A union connection for the apparatus is shown in Figs. 3 and 4 and 7 and 8. In the said figures the threaded tubular connection 24 is shown, the said connection being screw-threaded externally to fit the tapped opening 2 of the cover 1 and also screw-threaded internally to fit the tubular member 11 on the element 7. Upon attaching the connection 24 to the tubular element 11 and screwing same home thereon and also screwing the cover 1

onto the said connection the cover 1 is made attachable to the base 5 and the element 7, the rim flanges 3 and 4 on the cover 1 and base 5 being thus made to abut one another. The connection 24 may be used when the apparatus is intended for utilization either as for a pendent or for wall bracket attachment.

Further modifications of the apparatus are illustrated in Figs. 9 to 11. When openings 10 are required in the base 5 to enable the apparatus to be adapted for different uses these may be provided. In Figs. 9 and 10 the base 5 is shown with an opening to receive the projecting coupling 32 whose rear end is preferably furnished with a flange 33 to seat against the base 5. A cap 34 with serrated edge 35 abutting the base 5 fits about the coupling 32 and may be secured thereto by the screws 36. Such coupling may be internally screw-threaded to receive an externally screw-threaded conduit 37, but if the coupling is not internally screw-threaded a conduit may be attached thereto by means of a screw 38 which passes through the cap 34 and coupling 32 to the conduit 37. Ornamentation members 51 (Fig. 9) of suitable type may be attached to the cap 34 and coupling 32 by means of the screws 52, such members being furnished 25 with a hook 53 if required.

If a plug coupling Fig. 11 is to be used with the base 5 a metal case 54 may be attached by bolts 55 and nuts 56 to the base 5 and such casing may carry an electrical insulating block 57 having electric conductive tubes 58 for a plug connector 59 having projecting plug connector pins 60. The switch block 93 in Fig. 11 has associated therewith the conductive contact plates 96 with which 35 the movable conductive plate 97 may be made to contact or not, depending as to whether the switch operative means are set to "on" or "off" position.

If the apparatus is desired for junction use 40 the element 7 may have attached thereto (Figs. 2, 3, 4 and 10) either one or both the electric insulating blocks 69 preferably having the rib 70; these blocks may have suitable terminal means 71 and 72 thereon and 45 they may be secured to the element 7 by screws 73. A similar arrangement of insulating blocks 93 are shown in Figs. 8 and 11 in connection with the element 7 when designed for use with switch means; only 50 one such block (Fig. 11) is used if the switch is to be of the single pole type, but if of the double pole type (Fig. 8) two such blocks are used. When blocks are used for switch means of single pole type one of such blocks 55 93 may be used as a switch block and the other block may consist of a junction block 94. The rib 70 of the blocks 69 and 94 serves to 60 prevent contact between the lead wires to the terminals of such blocks. Only one fuse block 65 95 may be used if desired. In Fig. 9 the ele-

ment 7 is shown associated with a switch block 93 and also with a fuse block 95 of suitable type.

Referring to Fig. 3, the element 7 and base 5 are shown associated with the metal base plate 18, screws 19 being utilized to attach the plate 18 to the bottom of the base 5. The base plate 18 has a neck 63 whose inner end may abut the bottom of the base 5 when the base plate 18 is set on the base 5. The base plate 18 with parts of the apparatus attached thereto may be connected in any preferred manner to any suitable support.

It will be understood that the provision of the base plate 18 and the connection and construction of the various combinations of integers above described and illustrated in the drawings with the base 5, the latter being associated with the cover 1, offers means whereby if any short-circuiting of current should occur in using the apparatus the latter will be earthed and current may then flow to earth.

What I claim as my invention and desire to secure by Letters Patent is:-

1. An electric current distributor of the character described, comprising a base member, a cover therefor having a threaded opening, a U-shaped metal element mounted on the base and having an externally threaded neck, and a union screwed over the neck and into said opening in the cover to connect the latter to the base.

2. An electric current distributor of the character described, comprising a base member, a cover therefor having a threaded opening, a plate arranged at the bottom of the base, a U-shaped metal element secured to the plate and having an externally threaded neck, and a union screwed over the neck and into the opening in the cover to connect the latter to the base.

3. An electric current distributor of the character described, comprising a base member having a formed bottom surface, a cover therefor having a threaded opening, a plate arranged at the bottom of the base, a U-shaped metal element secured to the plate and having an externally threaded neck, a union screwed over the neck and into the opening in the cover to connect the latter to the base, and a base plate for the formed bottom surface of the base to provide a ground connection for the distributor.

4. An electric current distributor of the character described, comprising a base member, a cover therefor having a threaded opening, a U-shaped metal element mounted on the base and having an externally threaded neck, a union screwed over the neck and into the said opening in the cover over which the cover is screwed to connect the latter to the base, the opposite parallel sides of said element being formed as bearings for a rotary switch means associated with the element,

and a shield member embracing the element to protect the parts.

5. An electric current distributor as claimed in claim 1, in which the said base member is provided with a plurality of openings, a metal coupling having a flange seating within the base and about said openings, a metal cap fitting about said coupling and having one of its ends serrated and abutting said base, and means for securing said coupling and cap to each other.

6. An electric current distributor, as claimed in claim 1, in which the ends of the parallel portions are provided with lateral flanges, substantially as described.

15 In testimony whereof I affix my signature.

GEORGE RUDSTON BROWN.
